UNITED STATES PATENT OFFICE.

FRANCIS HOFER, OF BALTIMORE, MARYLAND.

DETACHABLE LAPEL.

Application filed April 16, 1928. Serial No. 270,293.

This invention relates to wearing apparel and has special reference to a false lapel.

The principal object of this invention is to provide a false facing for the lapels or 5 lapels and collar of an ordinary sacque coat so that these parts of the coat may appear to be covered with satin or silk in the ordinary conventional manner used in the construction of a dinner jacket or, as it is sometimes 10 called, Tuxedo. By this means any person having an ordinary black sacque coat may readily convert the same into a dinner jacket.

With the above and other objects in view 15 as will be hereinafter apparent, the invention consists in general of certain novel details of construction and combinations of parts hereinafter fully described, illustrated in the accompanying drawings and specifically 20 claimed.

In the accompanying drawings like characters of reference indicate like parts in the several views, and:

Figure 1 is a perspective view of a pair of 25 lapels constructed in accordance with this invention with the coat whereto they are applied shown in dotted lines.

Figure 2 is a view showing a modification 30 in which both the lapels and collar are made in one piece and applied as a unit to the coat.

Figure 3 is an inside view of a lapel constructed in accordance with this invention in its flat condition.

Figure 4 is a cross section on the line 4—4 35 of Figure 1.

Figure 5 is a detail perspective of one of the hooks used herewith.

Figure 6 is a detail perspective of one of 40 the spring clips used herewith.

In carrying out this invention the lapels or 45 lapels and collar of the invention are formed from a suitable strip of satin or other like material 10. This strip is provided with a proper lining 11 and at one edge, which may be termed the inner edge, there is secured on the inside of the strip a series 50 of hooks 12 somewhat like the hooks of an ordinary hook and eye but having a sharpened point or bill 13. These hooks as can be seen from Figure 5 are formed from a single length of wire. The other or outer

edge of the strip 10 is folded to provide a hem 14 to which is secured the hem 15 of a backing strip 16 which in use lies behind the 55 free edge of the coat lapel and collar 17, the body of the coat being indicated at 18. Along the last mentioned edge of the facing strip is arranged a series of U-shaped clips, the lights 19 of these clips being located 60 between the strips 10 and 16 with the legs 20 and 21 projecting inwardly. Each leg 20 is received between the strip 10 and lining 11 and is secured to the lining by stitching passing through holes 22. It will be observed that by this arrangement the spring 65 clips act in the two capacities of fastening means and stiffening elements thus holding the false lapels and collar neatly in shape. It will also be observed that by reason of the 70 employment of the sharp hooks the device may be applied to any coat without any previous preparation of the garment as would be necessary where snap buttons or 75 hooks and eyes were used since in the application of the device all that is necessary is to slip the clips over the lapel, double the remaining edge of the false lapel under the coat and hook the points 13 into the body or lining of the coat inside thereof. 80

There has thus been provided a simple and efficient device of the kind described and for the purpose specified.

It is obvious that minor changes may be made in the form and construction of the 85 invention without departing from the material spirit thereof. It is not, therefore, desired to confine the invention to the exact form herein shown and described, but it is desired to include all such as properly come 90 within the scope claimed.

Having thus described the invention, what is claimed as new, is:

1. A false lapel for coats including a facing adapted to cover a coat lapel and having 95 one edge arranged to underlie the coat body and an opposite edge portion arranged to underlie the edge of a coat lapel, means to secure the first edge detachably to the inside of the coat, and clamping and stiffening means carried by the false lapel and arranged to grip the coat lapel on both sides thereof.

2. A false lapel for coats including a fac-

ing adapted to cover a coat lapel and having one edge arranged to underlie the coat body and an opposite edge portion arranged to underlie the edge of a coat lapel, means to secure the first edge detachably to the inside of the coat, and spring clips having a bight portion and opposed spring legs, each clip

having one of its legs secured to the false lapel with the bight portion at the second edge of the false lapel, the remaining leg ¹⁰ of each clip being free and engageable beneath the coat lapel.

In testimony whereof I affix my signature.
FRANCIS HOFER.
